UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A BACK FOR BRUSHES.

SPECIFICATION forming part of Design No. 24,537, dated August 13, 1895.

Application filed June 26, 1895. Serial No. 554,143. Term of patent 7 years.

To all whom it may concern:

Be it known that I, CHARLES C. WIENTGE, of the city of Providence, in the county of Providence and State of Rhode Island, have 5 invented and produced a new and original Design for Backs of Brushes and Similar Articles, of which the following is a specification, reference being had to the accompanying drawings, forming part thereof.

10 The essential features which characterize the design consist in the central compound convexity of the back, the slightly upwardly-curved projections at the ends, the handle extending from one of such projections and 15 having the indented end, together with surface ornamentation, to accentuate the outline.

Figure 1 represents a view of a back for brushes and similar articles, showing the general characteristics of the new design, the 20 surface ornamentation being shown in dotted lines. Fig. 2 represents an edge view of the same, showing its adaptation for the back of a brush.

In the drawings, 5 indicates the back proper,

and 6 the handle portion. The outline, commencing at the convex projection 7, extends inward to 8 8, then outward to form the rounded convex corners 9 9, then curves gradually along the sides of the back to 10 10, thence inwardly again to 11 11 to join the 30 outward curves 12 12 of the handle 6, which extends to 13 13, and then curves inward over the end of the handle to form the indentation 14. The general contours of the back and of its handle consist in the general transverse 35 convexity of these parts, the upwardly-turned end 15 forming the surface of the projection 7, the longitudinal convexity 16 of the back, and the generally convex curved handle.

What I claim is—

The design for backs of brushes and similar articles as herein shown and described.

In witness whereof I have hereunto set my hand.

CHARLES C. WIENTGE.
